UNITED STATES PATENT OFFICE.

CLARENCE N. CAHUSAC, OF JERSEY CITY, NEW JERSEY, ASSIGNOR TO SLOCUM, AVRAM & SLOCUM, INC., OF NEW YORK, N. Y., A CORPORATION OF NEW YORK.

ELECTRIC COUNTER.

1,273,820.

Specification of Letters Patent. Patented July 30, 1918.

Application filed March 7, 1917, Serial No. 153,159. Renewed December 20, 1917. Serial No. 208,147.

To all whom it may concern:

Be it known that I, CLARENCE N. CAHUSAC, a citizen of the United States, and resident of Jersey City, in the county of Bergen 5 and State of New Jersey, have invented certain new and useful Improvements in Electric Counters, of which the following is a specification.

My invention relates to electric counters, 10 and has for its object to provide a novel manner of mounting the armature of the magnet which is energized to impart the electric counting impulse, whereby said impulse will be imparted to the counting 15 mechanism positively and with a minimum of current.

This object I accomplish in the manner and by the means hereinafter described and claimed, reference being had to the accompanying drawing, in which:—

Figure 1 is a side elevation of my improved device shown associated with a conventional counter.

Fig. 2 is a top plan view of the same.

Similar numerals of reference denote corresponding parts in the two views.

In the said drawing the reference numeral 1 denotes a base plate having upturned ends 2, to which the core-piece 3 of the 30 magnet is screwed or otherwise attached. Said core-piece 3 is provided with a winding 4 of fine insulated wire, the terminals 5 of which are to be connected with any suitable source of electrical power and 35 mechanism whereby intermittent electrical impulses will be imparted thereto. Said core-piece projects from both ends of the winding 4, thus providing a pole at each end thereof.

40 Mounted pivotally at 6 in brackets 6' fixed to the base-plate 1 are the longitudinal bars 7 of a rectangular armature frame, the cross-bars 8 of which form armatures at the opposite ends of the magnet, the bar 45 8 at one end being disposed beneath the pole-piece 3, while the bar 8 at the other end is disposed above said pole-piece. One of the longitudinal bars 7 is extended at 9, at one end, and is slotted at 10 to receive a 50 bolt 11 which is passed through one of a series of holes 12 in a lever 13 fixed to the shaft 14 of a conventional step-by-step counter 15 which is bolted to one of the upturned ends 2 of the base-plate 1, said counter

being provided with the usual resetting 55 hand-wheel 16, as shown.

The operation of my improved device is as follows:—The frame, composed of the longitudinal bars 7 and the cross armatures 8, which is pivoted intermediate its length 60 at 6, is adapted to rock freely on said pivot, and is retained normally in the position shown in Fig. 1 partly by the greater weight of the right-hand end of said frame and partly by the tension of the spring mechanism in the counter 15, which is exerted through the lever 13 to force upwardly the left-hand end of said frame. Now when an electrical impulse is imparted to the magnet, the core-piece 3 will be energized, thereby attracting toward it both of the armatures 8, which necessarily will rock the frame of which they are a part so as to depress the end nearest the counter 15, thereby 70 rocking the lever 13 and imparting a counting impulse to the counting mechanism in the usual manner. When the magnet is de-energized the frame instantly will assume its normal position shown in Fig. 1, resetting the counting mechanism for the 75 next impulse.

The primary advantage of this construction is that the armatures are pivoted with respect to the magnet so that they are substantially counterbalanced, and a very light 85 electrical impulse imparted to the magnet will cause an operation of the mechanism.

Having thus described my invention, what I claim as new and desire to secure by Letters Patent is:—

In a device of the class described, a magnet having a pole at each end of its winding, an armature frame comprising longitudinal bars and pivoted intermediate its length and inclosing said magnet, and an 95 armature at each end of said bars adapted to be attracted by one of said magnet poles, one of said bars being formed into a slotted extension at one end, in combination with mechanism to be operated, and a lever connected with said mechanism to operate the same and also connected with the slotted extension of said armature frame to be vibrated thereby.

Signed at the city of New York in the 105 county and State of New York, this 22nd day of February, A. D. 1917

CLARENCE N. CAHUSAC.
